UNITED STATES PATENT OFFICE.

FRIEDRICH ELLER, OF FRANKFORT-ON-THE-MAIN, GERMANY, ASSIGNOR TO
ALLGEMEINE ELEKTRISITÄTS-GESELLSCHAFT, OF BERLIN, GERMANY.

TICKET-PRINTING APPARATUS.

1,077,194.

Specification of Letters Patent.

Patented Oct. 28, 1913.

Application filed February 25, 1913. Serial No. 750,553.

To all whom it may concern:

Be it known that I, FRIEDRICH ELLER, a subject of the King of Prussia, and resident of Frankfort-on-the-Main, Germany, have invented certain new and useful Improvements in Ticket-Printing Apparatus; and I do hereby declare the following to be a full, clear, and exact description of the invention, such as will enable others skilled in the art 10 to which it appertains to make and use the same.

This invention relates to ticket printing apparatus and more particularly to an apparatus for printing tickets, such as railway 15 tickets automatically, and in which the individual printing blocks, plates or forms are stacked in a suitable magazine or receptacle and are adapted to be brought into any desired selective connection with the printing 20 mechanism by a displacement of the latter and of the said receptacle or magazine respectively.

The object of this invention is to effect, after the attendant has indicated the ticket 25 to be printed by manipulating a suitable selector device or member as a plug, a key, a lever or the like, automatically the whole of the movements necessary for the selection of that printing block, its insertion in the 30 printing mechanism, the printing operation and the reintroduction of the printing block into its magazine without any substantial exertion of force in operating the apparatus.

Another object of the invention is to render 35 the apparatus and its internal arrangement inaccessible to the attendant so as to avoid any irregular manipulations.

To this end according to this invention I provide in connection with the individual 40 selection devices which are suitably arranged on a wall or panel and correspond to the different printing blocks or forms, adjustable abutments or stops which by the use of the selection devices are caused to limit 45 the relative movements of the printing block container or magazine and the printing mechanism respectively at a point or points predetermined by the selection made so as to enable the selected printing block to be 50 inserted in the printing mechanism. These abutments or stops may be formed either by the adjusting means actuated in the manipulation of the particular selection device or by separate stops in which latter case they 55 are brought into their limiting position by

the selection device employed in selecting that particular field. The latter arrangement is preferable where the movements of the magazine and of the printing mechanism take place in different directions, that is to say, in the case in which the printing blocks are arranged side by side and one above the other. In this case as many stops have to be adjusted from each selection device as there are directions of movement. The 60 abutments or stops may be adjusted either mechanically or electrically. In order to still further facilitate the handling of the apparatus, the selection device may also be used for starting and stopping the driving 70 mechanism so that the whole of the actions ending with the delivery of the printed ticket are started by a single manual operation.

In the accompanying drawings the invention is illustrated by way of example in the form of an apparatus for printing railway tickets with mechanically adjustable limiting stops:

Figure 1 and Fig. 1^a taken together are a 80 total view of the arrangement in front elevation, partly in section. Fig. 2 shows a lateral elevation partly in section. Fig. 3 is a plan view, Fig. 4 shows in detail a portion of a printing block magazine in longitudinal 85 section. Fig. 5 is a detail side view of the printing mechanism and the arrangement for driving the same. Fig. 6 is a perspective detail view showing more particularly the means for transferring a printing block to 90 the printing roller.

The device comprises mainly a casing 1 containing the printing blocks, a printing mechanism 2 and a panel 3 with selection 95 divisions or fields 4. The casing 1 is divided into a number of vertical compartments or magazines 5 located side by side. In these magazines the individual printing blocks 6 are superposed, as shown in Figs. 4 and 6. It is important that the printing mechanism 2 and the magazines 5 should be capable of relative displacement so that a selected printing block may be brought in front of a printing roller 7 and introduced therein by means of a suitable device. To this end 100 the printing mechanism 2 is adjustably arranged upon a carriage 9 horizontally movable on rollers 8, which run upon track 9' whereby it may be brought in front of the individual magazines 5. The mechanism is 105 110

driven by a suitable motor 10 which may, for instance, be an electromotor coupled with a driving shaft 11. Mounted on this shaft is a sprocket wheel 12 for the actuation of 5 a ratchet gear 13 which is arranged on the printing mechanism shaft 14. Mounted, moreover, on the driving shaft 11 is a reversing gear 15 adapted to drive a shaft 18 by means of a sprocket gearing 16 and 17.

10 Arranged on the shaft 18 and located within the printing mechanism 2 is a differential gearing 19 which on being driven first actuates the printing mechanism and on the latter being brought to a standstill, 15 operates to raise or to lower one of the magazines 5. The movement of the printing mechanism is caused by a beveled gear 19¹ suitably mounted to be turned by shaft 18 and to slide longitudinally thereon, engaging a beveled gear 19² on the shaft of the differential gear 19. This differential gear comprises two bevel gears 21¹ and 21² between which rolls the bevel gear 22¹ mounted on the shaft of the differential gear. The bevel gear 21¹ carries the pinion 20 which operates in the teeth of rack 21 to cause the carriage 9 to move there along. The bevel gear 21² carries the pinion 22 which operates in the teeth of a rack 23 having a lug 24 at the bottom thereof which 25 engages the bottom of the magazine 5 to raise the same. The energy required to move the carriage 9 is considerably less than that required for lifting a magazine 5.

30 During the movement of the printing mechanism therefor the pinion 22 and bevel gear 21² remains stationary and the turning of bevel gear 19² causes the bevel gear 22¹ to drive bevel gear 21¹ and hence move the 35 carriage along the rack 21. When the printing mechanism is brought to a standstill the motion of pinion 20 closes and bevel gear 22¹ now drives bevel gear 21² and through pinion 22 lifts the vertical rack 23 to elevate 40 a magazine 5. The selection table 3 arranged above this mechanism contains the selection divisions or fields 4 which in the example illustrated have the form of rectangular apertures or square holes designated by suitable inscriptions as shown in Fig. 1, indicating for instance the names of different towns or stations corresponding to the printing blocks to be selected. These 45 selection divisions or holes coincide in their positions with the printing blocks contained in the magazines. The selecting element arranged in this case for the manipulation of the apparatus is a plug 25, which is inserted into the particular hole 4 according to selection, as shown in Fig. 3. In the rear of each 50 vertical row of selecting holes 4 is located a vertical bar 26 which is provided with apertures 27 corresponding in number with the number of selecting holes 4. These apertures are situated behind the selecting holes

4 so that the plug 25 on being inserted in a selecting hole projects through both the latter and its registering aperture and thereby depresses the corresponding bar 26 to a determined extent. Arranged beneath each 70 bar 26 is one end of a two-armed lever 28, Figs. 2 and 3, on the other end of which rests a spring-actuated stop pin 29. These stop pins 29 serve for limiting the horizontal movement of the printing mechanism, to 75 which end the latter is provided with an abutment 30 adapted to coöperate with these stops. One stop is provided for each magazine 5 so that the printing mechanism may be brought to a standstill in front of the 80 selected magazine.

Connected with the printing mechanism is a normally empty compartment 31 which is moved with the printing mechanism across the magazine 5 containing the printing blocks situated beneath it and which has such cross section as to enable it to receive one of the magazines 5. Provided on one side or wall of the compartment 31 are as many adjustable abutments 32 as 85 there are printing blocks in each magazine. These abutments 32 are integral with or connected to levers 33 which are rotatably journaled about vertical pivots 34 in the upper compartment 31. The free ends of 90 the levers 33 extend close to the vertical bars 26 and are located substantially flush with the selecting holes 4 so as to enable them to engage with the plug 25, as will be readily understood from Fig. 2. By this 95 engagement the abutment 32 connected with the lever 33 thus struck is actuated or forced into the compartment 31 as shown in Fig. 4. Arranged on the top of each magazine 5, moreover, is a sliding bolt 35 which as soon 100 as it comes into contact with the operative abutment 32 in the compartment 31 during the ascent of the magazine 5, is caused by that abutment to enter a toothed bar 36, as shown in Fig. 4, which is vertically movable 105 in the compartment 31. This bar 36 bears with its upper end against the underside of a rocking bar 37 which by means of a connecting rod 38, a bell crank lever 39, a link 40, a bell crank lever 41 and a pitman 42 is 110 adapted to actuate a locking arrangement 43 provided for the operation of the reversing gear 15. The two locking pawls 43 engage alternately with a locking rod 45 which is 115 under the influence of a traction spring 44 and is connected with two movable clutch members 46 and 47 of the reversing gear 15.

When a particular ticket for a particular station is required, the plug 25 is inserted in the corresponding selection hole 4. By 125 this action the vertical bar 26 located in the rear of the selected hole is depressed thereby rocking the lever 28 located beneath it which thus raises the corresponding stop 29, as will be clearly understood from Fig. 2. If 130

now the driving motor 10 is started which may be effected simultaneously with the insertion of the plug, either by the latter itself or the bar 26 closing an electric contact, the driving movement thus derived is transmitted by means of the reversing gear 15 and the chain gearing 16, 17 to the shaft 18. The differential gear 19 driven by this shaft 18 then moves, by means of the toothed wheel 20, the printing mechanism 2 along the rack 21 until it strikes the raised stop pin 29. As soon as the further movement of the printing mechanism is thus arrested the differential gearing owing to the resistance of the stop pin is actuated as explained above with the result that now its toothed wheel 22 is caused to actuate the toothed rack 23 in upward direction. In this movement this rack by means of its lateral projection 24 raises the respective magazine 5 with the printing blocks arranged therein and moves it into the empty compartment 31 located above it. Shortly before the printing mechanism strikes the stop 29 one of the levers 33 arranged in the compartment 31 abuts against the inwardly projecting end of the plug 25 whereby with the aid of this lever the abutment 32 connected with it is pressed into the compartment 31. Now as soon as the magazine 5 containing the printing blocks has risen in the compartment 31 till the bolt 35 strikes the protruding abutment 32 the bolt 35 is forced into engagement with the toothed bar 36 which is now raised together with the magazine 5 until the latter is limited in its movement by the abutment 32. At this moment the printing block corresponding to the selected hole 4 is situated in front of the printing roller in which it is to be inserted. The rising bar 36 now raises the rocking bar 37 which by means of the transmission members 38 to 42 above referred to releases the operative locking pawl 43 after which under the action of the traction spring 44 the locking rod 45 is retracted until the other pawl 43 becomes operative. By this movement the reversing gear 15 is thrown out of action and the driving of the shaft 18 ceases. At the same time by the rocking of the bell crank lever 39 a pin 48 is withdrawn from the ratchet gear 13 thereby enabling the printing shaft 14 to make one revolution. During this revolution of the printing shaft 14 a pusher 49 arranged on the printing mechanism is so actuated by means of a cam disk 49' as to cause its projecting arms 75 to enter the compartment 31 and to push the printing block located in line therewith in the magazine 5 from this magazine into a recess 50 in the printing roller 7. The platen 51 now moves forward and by means of a lug carries with it a blank ticket from a magazine 52 at the same time rotating the printing roller by

means of a toothed rack so that the selected printing block is impressed upon the ticket located on the platen. When the platen has reached the end of its forward movement the printed ticket is caught by a suitable catch 58 and is wiped off, as the platen returns to its initial position. In this movement the printing roller also is brought back to its initial position and the printing block just employed is moved back to its original place in the magazine by the annular lug 76 of the pusher 49.

The movements above described are effected by means of the arrangement as shown in Figs. 1, 5 and 6, wherein the cam disk 49' is shown as having a cam slot 60 in which rides one end of a pivoted lever 61, the opposite end of said lever being attached to the pusher 49. The cam disk is mounted on a shaft 62, which shaft is given a one-half revolution by means of star wheel 63 and member 64 during the revolution of the printing mechanism shaft 14. The shaft 62 carries two mutilated gears 65 and 66. The cycle of operation is as follows: The first movement of the cam disk 49' rides the end of the lever 61 down the angular portion of the cam slot 60 thereby forcing a printing block 6 into the slot 50 of printing roller 7. At the end of this movement the teeth 67 of gear 65 engage pinion 68 and through the intermediate gears 69 roll the platen 51 forward to effect the printing of the ticket. At the end of this forward movement teeth 67 run beyond pinion 68 and teeth 71 on gear 66 now engage pinion 72 which through the intermediate gears 69 returns the platen and printing roller to their initial position, the teeth 71 disengaging from pinion 72 at the end of this return movement. The end of lever 61 which during the forward and return movements just described has been moving across the straight portion of cam slot 60 now rides up the angular portion of such cam slot and moves the pusher to return the printing block to its original place in the magazine 5. When the rotation of the printing shaft 14 is almost completed a cam disk 53 arranged on this shaft actuates a lever 54 by which the reversing gear is so set as to cause the magazine and the printing mechanism both previously raised by the shaft 18 to return to initial position. At the same time by means of pawls 56 and 57 arranged on the carriage 9 and on a connecting rod 55 respectively, the locking device 43, 44 and 45 of the reversing gear is re-set and the driving power stopped in a suitable manner.

Having now fully described and ascertained my said invention, and the manner in which it is to be performed, I declare that what I claim is:

1. In an apparatus for printing tickets or the like, a plurality of compartments, type

- blocks in said compartments, a printing mechanism, said printing mechanism and compartments being arranged for movement relative to each other, whereby any compartment may be brought into alinement with said printing mechanism, means associated with the printing mechanism for moving a compartment relative to the printing mechanism, a type block selecting means, and means automatically brought into operation upon the operation of said type block selecting means to first bring the selected compartment and printing mechanism into alinement and to then operate the said compartment moving means to move the selected compartment relative to said printing mechanism.
2. In an apparatus for printing tickets or the like, a plurality of type block carrying members arranged side by side, type blocks carried by said members, a printing mechanism, said printing mechanism and carrying members being arranged for movement relative to each other whereby any carrying member may be brought into alinement with said printing mechanism, means associated with the printing mechanism for moving a carrying member relative to the printing mechanism, a type block selecting means, and means automatically brought into operation upon the operation of said type block selecting means, to first bring the said carrying member and printing mechanism into alinement and to then operate the said carrying member moving means to move the selected carrier relative to said printing mechanism.
3. In an apparatus for printing tickets or the like, a magazine having movable compartments, type blocks in said compartments, a printing mechanism mounted adjacent to said magazine for movement relative thereto, means carried by the printing mechanism for moving a compartment relative to the printing mechanism, a type block selecting means, and means automatically brought into operation upon the operation of said type block selecting means to first move said printing mechanism adjacent to the compartment containing the selected type, and to then operate said compartment moving mechanism to move the selected compartment relative to said printing mechanism, and automatic means controlled by the movement of the compartment for moving the selected type into the printing mechanism, and for starting said printing mechanism into operation.
4. In an apparatus for printing tickets or the like, a magazine having movable compartments, type blocks in said compartments, a printing mechanism including a printing roller mounted adjacent to said magazine for movement relative thereto, means carried by the printing mechanism for moving a compartment relative to the printing roller, a type block selecting means, and means automatically brought into operation upon the operation of said type selecting means to first move said printing mechanism adjacent to the compartments containing the selected type and to then operate the said compartment moving mechanism to move the selected compartment relative to said printing mechanism.
5. In an apparatus for printing tickets or the like, a magazine having movable compartments, type blocks in said compartments, a printing mechanism mounted adjacent to said magazine for movement relative thereto, means carried by the printing mechanism for moving a compartment relative to the printing mechanism, a type block selecting means, means automatically brought into operation upon the operation of said type block selecting means to first move said printing mechanism adjacent to the compartment containing the selected type, and to then operate said compartment moving mechanism to move the selected compartment relative to said printing mechanism and automatic means controlled by the movement of the compartment for moving the selected type into the printing mechanism.
6. In an apparatus for printing tickets or the like, a magazine having movable compartments, type blocks in said compartments, a printing mechanism mounted adjacent to said magazine for movement relative thereto, means carried by the printing mechanism for moving a compartment relative to the printing mechanism, a type block selecting means, means automatically brought into operation upon the operation of said type block selecting means to first move said printing mechanism adjacent to the compartment containing the selected type, and to then operate said compartment moving mechanism to move the selected compartment relative to said printing mechanism and automatic means controlled by the movement of the compartment for moving the selected type into the printing mechanism.
7. In an apparatus for printing tickets or the like, a plurality of vertically movable compartments arranged side by side, type blocks in said compartments, a printing mechanism mounted adjacent to said compartments for movement therewith, a stop appurtenant to each compartment adapted to be moved into the path of movement of said printing mechanism, means carried by said printing mechanism for moving a compartment vertically relative to said printing mechanism, a type block selecting means, means operated upon the operation of said selecting means for elevating the stop peculiar to the compartment containing the selected type block into the path of movement of said printing mechanism, means brought into operation upon the operation of said selecting means for caus-

ing the printing mechanism to move along said compartments, and means whereby when said printing mechanism engages said stop, said compartment moving means is brought into operation to move said selected compartment vertically relative to said printing mechanism.

8. In an apparatus for printing tickets or the like, a plurality of vertically movable compartments arranged side by side, superposed type blocks in said compartments, a printing mechanism mounted adjacent to said compartments for movement therewith, means for moving a compartment vertically relative to said printing mechanism, stops appurtenant to each compartment for limiting the movement of the printing mechanism and of each compartment, a type block selecting means, means operated upon the operation of said type block selecting means for moving the stop appurtenant to the selected compartment

into the path of said printing mechanism and for moving the stop appurtenant to the selected type block into the path of movement of said compartment, means brought into operation upon the operation of said selecting means for causing the printing mechanism to move along said compartments, means whereby when said printing mechanism engages said stop, said compartment moving means is brought into operation to move said selected compartment vertically relative to said printing mechanism, and means operated by the engagement of said compartment with its stop for limiting the further movement thereof.

In testimony whereof I affix my signature, in presence of two witnesses.

FRIEDRICH ELLER.
